CLAIM

The ornamental design for an aquatic exercise bottle, as shown.

DESCRIPTION

FIG. 1 is a front elevational view of an aquatic exercise bottle showing my new design, the back view being a mirror image thereof;

FIG. 2 is a side elevational view thereof, the opposite side being a mirror image thereof;

FIG. 3 is a top plan view with a cut away from section

thereof, the bottom view being a mirror image thereof;

FIG. 4 is a cross-sectional view thereof, taken along

4—4 in FIG. 3; and,

FIG. 5 is a perspective view of my new design.

FIG. 3

FIG. 4
